Patented Oct. 11, 1921.

UNITED STATES PATENT OFFICE.

DAVID GLICKMAN, OF CHICAGO, ILLINOIS.

SUSPENDERS.

1,392,935.

Specification of Letters Patent. Patented Oct. 11, 1921.

Application filed June 17, 1918. Serial No. 240,350.

To all whom it may concern:

Be it known that I, DAVID GLICKMAN, a citizen of the United States of America, and a resident of Chicago, county of Cook, and 5 State of Illinois, have invented certain new and useful Improvements in Suspenders, of which the following is a specification.

This invention relates to garment supporting means of the type known as suspenders, 10 and the main objects of the invention are to provide an improved form of suspender to be worn underneath the outer shirt and adapted to be attached to the trousers buttons in about the same manner as ordinary 15 suspenders but with the outer shirt fabric gripped over the button; to provide such a device adapted to be connected detachably directly to the underwear for supporting the trousers and obviating the necessity of wearing 20 a belt, either outside or inside of the trousers or suspenders running over the shoulder; and to provide a suspender adapted to be concealed by the shirt when worn without coat or outer garment, and requiring 25 but little material for manufacture and which shall be durable but inexpensive.

An illustrative embodiment of this invention is shown in the accompanying drawings, in which—

30 Figure 1 is a perspective view showing how the suspender is applied to the garments when in place on the wearer.

Fig. 2 is a front elevation of one form of the suspender illustrating this invention.

35 Fig. 3 is a vertical sectional view of the adjacent parts of the garments with the suspender attached thereto, the latter being shown edgewise.

Fig. 4 is a front elevation of the upper 40 end of one of the suspenders showing a modified form of fastening.

In the illustrative embodiment shown in the drawings, Figs. 1 to 3, the suspender 1 is of forked shape with the two divergent 45 arms projecting downward from the crotch 2, and comprises a flexible strap or body member of fabric tape, or other suitable material, with a common fastener 3 at the upper or crotch end, and with separate fasteners 4 at the opposite or lower ends of the branches 5.

The fastener 3 is adapted to be detachably connected directly to the undergarment 6, as shown in Fig. 1, and the fasteners 4 are 55 apertured and adapted to receive the buttons 7 of the trousers 8 as also shown in Fig. 1,

said fasteners 4 being also adapted to receive or accommodate a thickness of the material of the outer shirt 9 between the button and the body of the fastener loop, so that the suspender may be entirely covered and concealed by the outer shirt.

The fasteners 4 are of rigid material and are each formed with a substantially circular button admitting aperture 10 and a 60 notch or socket 11 extending downward therefrom to receive and securely hold the button when the device is in use. In order to better secure the button in the socket 11 each fastener 4 is provided with a hump 12. 65

The upper fastener 3 is formed and adapted to receive a pinch of garment fabric, whereby it may be fastened detachably to the underwear beneath the outer shirt. For this purpose a wedge shaped aperture 13 is 75 preferred with a narrow pinching slit 14 at the upper pointed end of the fastener to engage a small pinch 9' of the under garment for supporting the suspender.

In the modified form of device shown in 80 Fig. 4, the upper fastener 3' is provided with a wider pinch slit 14', and a flexible lock tongue 15 having a head 16 is provided, substantially as in some forms of garters.

Although two specific embodiments of 85 this invention are herein shown and described, it is to be understood that no attempt has been made to show all practical embodiments and that numerous details of the constructions shown may be altered or 90 omitted without departing from the spirit of this invention as defined by the following claim.

I claim:

Trousers supporting means adapted for 95 wearing under the outer shirt comprising a pair of short suspenders secured at their upper ends to a single fastener and disposed at an angle to each other, said fastener being adapted to be pinchingly connected detachably to the under shirt, and a fastener attached to the lower end of each of said suspenders, each of said latter fasteners having a looped part large enough to receive the body of a button and communicating with a 100 downwardly disposed notch, said latter fasteners being adapted to receive trousers buttons with the adjacent part of the outer shirt gripped thereby.

Signed at Chicago this 13th day of June 110
1918.

DAVID GLICKMAN.
